UNITED STATES PATENT OFFICE

OLIVER C. K. HUTCHINSON, OF ALTON, ILLINOIS, AND JOHN E. McLAUGHLIN AND LEONARD D. SOUBIER, OF TOLEDO, OHIO, ASSIGNORS TO OWENS-ILLINOIS GLASS COMPANY, OF TOLEDO, OHIO, A CORPORATION OF OHIO

GLASSWARE FORMING MACHINE

Application filed July 29, 1929. Serial No. 381,782.

The present invention relates to improvements in glassware forming machines and more particularly to means by which formation of the usual cutoff scar on the bottoms of articles of glassware, such as bottles and jars, may be materially reduced, if not entirely avoided.

In glassware forming machines embodying suction blank molds, it is standard practice to sever mold charges of glass in the molds from a supply body of the molten glass, by means of knives which are moved laterally across the lower ends of the molds after each charging operation. Each cutoff knife 15 includes a closure plate which moves along a path at right angles to the axis of the mold cavity and is brought into position to close the lower end of the mold immediately following severance of the charge of molten 20 glass from the supply body. When the closure plate is in position to close the lower end of the mold cavity, it forms with the lower end of the cavity wall a relatively sharp corner which chills the glass around 25 the margin of the lower end of the blank to such depth that it cannot be reheated sufficiently prior to final expansion of the blank to avoid the formation of a scar in the finished article. This deep chilling of the glass 30 is in part due to the necessarily comparatively cool knife, but mainly to the fact that the wall of the cavity and the upper side of the cutoff knife are disposed approximately at right angles to each other, with the result that 35 the glass around the lower margin of the blank is subject to chilling on two sides.

An object of the present invention is to overcome the objection above pointed out and to provide means by which chilling of the 40 glass around the lower margin is materially reduced and rendered more nearly uniform by avoiding the formation of right angularly disposed surfaces for contact with the glass. To this end the cutoff knife is provided with 45 a recess or cup adapted to be brought into register with the mold cavity, said cup having side walls so shaped that the lower marginal corner of the blank which is expanded into the cup is not subject to such chilling as that 50 ordinarily encountered.

Other objects of our invention will be in part apparent and in part pointed out hereinafter.

In the drawings:

Fig. 1 is a sectional elevation of a charge 55 gathering unit embodying our invention.

Fig. 2 is a detail sectional elevation showing the cups or recesses in register with the mold cavities, just after completion of the 60 mold charging operation.

Fig. 3 is a fragmentary elevation showing the cups lowered away from the mold.

Fig. 4 is a fragmentary plan view of the 65 knife, showing the arrangement of the cups therein.

Fig. 5 is a detail sectional view illustrating the manner in which the blanks or parisons are chilled by apparatus of standard construction.

Fig. 6 is a detail view showing our recessed 70 cutoff knife, which avoids undesirable chilling of the blank.

Figs. 7 to 11 inclusive, illustrate another 75 form of cutoff knife embodying the cups or recesses.

Fig. 7 is a fragmentary front elevation.

Fig. 8 is a fragmentary sectional view 80 taken along the line VIII—VIII of Fig. 10, showing the mold and cutoff while gathering a charge of molten glass.

Fig. 9 is a view similar to Fig. 8, taken along the line IX—IX of Fig. 11, showing the relative positions of the mold and knife after the charge severing operation.

Figs. 10 and 11 are sectional plan views 85 showing the cutoff knife in the positions occupied prior to and following the charge severing operation, respectively.

In Figs. 1, 2, 3, 4 and 6 illustrating one embodiment of our invention, a single head 90 12 of a forming machine is shown, said head including a frame carrying a suction gathering mold 13 and neck mold 14, the latter connected to a vacuum chamber 15. The mold 13 is formed with a cavity which opens through its lower end. When the mold is brought into contact with the glass 17, the air is exhausted from said cavity and replaced by a measured quantity of said molten glass. 95 Exhaust of air from the mold cavity is con- 100

trolled by a valve 18 in said vacuum chamber 15, the valve being operated at regular time intervals by the usual well known mechanism.

Means to sever the mold charges in the cavity 16 from the supply body of glass 17 includes a cutoff knife 19 provided along one margin of a closure plate 25 and movable therewith laterally across the lower end of the mold immediately following lifting of the mold away from the supply body of glass and before the mold passes beyond the tank containing said glass. The knife and closure plate are supported on a vertical rock shaft 20, journaled at its lower end in a bearing 21 formed on an arm 22, extending to one side of and from said vacuum chamber 15. This shaft is oscillated and reciprocated at regular time intervals by rack and pinion mechanism 23 and a forked lever 24, respectively, in the usual manner. The foregoing is ordinary structure and for additional details relative to actuation of the cutoff mechanism, reference may be had to LaFrance Patent 1,185,687, dated June 6, 1916.

In order to prevent excessive chilling of the glass about the margin of the lower ends of the blanks as referred to above, the cutoff is provided with a pair of recesses 26 or vacuum cups, which are formed in the upper side of the closure plate 25 and adapted to register with the mold cavities and form extensions thereof at regular time intervals. Each cup 26 includes a substantially flat bottom 33 connected around its margin to side walls 32 which are curved transversely of their length substantially throughout their height. Thus, the formation of a right angle or relatively sharp corner at the juncture of the bottom and side walls of the cups is entirely avoided, with the result that the glass around the lower margin of the blanks is chilled only to the same depth as the remaining surfaces. Even distribution of glass in the finished article is one result of such uniform chilling.

Ordinarily the cavity wall 34 (Fig. 5) and upper face 35 of the cutoff knife provide a relatively sharp corner into which the lower margin 36 of the blank is pressed and deeply chilled. This portion cannot be sufficiently reheated prior to final blowing of the blank to avoid presence of the scar in the bottom of the finished article. Accordingly, the bottom of the finished article is unsightly and weaker than the remaining structure.

Air is exhausted from the cups while in register with the cavities to cause the blanks to extend into said cups. Such removal of air from the cups 26 is obtained by connecting them through vertical slots 27 and conduits 28 to an axial passageway 29 in the rock shaft 20, said passageway adapted for communication at regular time intervals with the vacuum chamber 15. Periodic communication between the passageway 29 and the vacuum chamber 15 is obtained by providing

a port 30 (Fig. 1) extending radially from the upper end of said passageway and adapted to register with one end of a conduit 31 in the arm 22, said conduit leading to the vacuum chamber 15. When the cutoff knife is in a plane to swing laterally across the lower end of the mold, the port 30 is horizontally aligned with the adjacent end of the conduit 31. With lateral movement of the knife and partial rotation of the rock shaft 20, this port 30 is brought into register with said end of the conduit 31, with the result that air is exhausted from the recesses 26 or cups. By exhausting the air from these cups, a portion of the glass in the mold 13 is moved lengthwise of the cavities 16 and completely fills the cups 26 as stated above.

In operation, the mold 13 is brought to a charge gathering position, as shown in Fig. 1, where measured quantities of molten glass are drawn into the cavities 16 by suction. The mold is then lifted and the cutoff swung laterally across the lower end of the mold by operation of the rack and gear mechanism 23. This movement of the knife severs the glass in the mold cavities from the supply body 17 and brings the recesses or vacuum cups 26 into register with said mold cavities. Such movement of the knife also positions the port 30 (Fig. 1) so that the air may be exhausted from said vacuum cups 26 to cause downward movement of the glass in the blank mold to fill said cups. Incidentally, this exhaust of air from the cups tends to bring the adjacent surfaces of the closure plate 25 and blank mold 13 into exceptionally snug contact with each other, resulting in elimination of the fin of glass which is frequently found just above the lower corners of bottles and jars.

In another form of the invention, Figs. 7 to 11, inclusive, the cutoff comprises a plate 37, mounted at the lower end of a rock shaft 38 and adapted to be positioned beneath the mold 13 during gathering of charges of molten glass from the supply body 17. The plate 37 is provided with a pair of vertical openings 39, which are brought into register with the mold cavities 16 prior to movement of the mold into a charge gathering position. When the air is exhausted from the mold cavities, measured quantities of molten glass are drawn into the mold cavities by way of said openings or passageways 39. Lateral movement of the plate 37 relative to the mold severs the mold charges from the supply body and closes the lower ends of the cavities. Severance of the glass is obtained by providing a shearing edge 40 at the upper end of each opening 39 to cooperate with the lower end 41 of the wall of each mold cavity.

A pair of recesses 42 or cups formed in the upper side of the plate 37 are brought into register with the lower ends of the mold cavities, due to lateral movement of said

- plate, and form extensions of the cavities as in the previously described form. These recesses or cups 42 are connected through vacuum slots 43 and conduits 44 in the cutoff 5 arm 45 to a passageway 46 extending lengthwise of the rock shaft 38, said passageway being adapted to communicate at regular time intervals with the vacuum chamber 15 by way of the port 30 and conduit 31. In this 10 form (Figs. 8 and 9), the vacuum cups or recesses 42 are hemispherical in shape so that the formation of angularly disposed surfaces for contact with the lower margin of the glass blank is avoided.
- 15 In operation, the plate 37 is positioned as shown in Figs. 7, 8 and 10, while the molten glass is being introduced into the mold cavities. Lateral movement of the plate severs the mold charges from the supply body and 20 brings the vacuum cups or recesses 42 into register with the mold cavities, as shown in Figs. 9 and 11. By exhausting the air from said cups while in register with the mold cavities, portions of the glass are drawn 25 downwardly to fill said cups substantially as shown in Fig. 9. The plate 37 is moved downwardly away from the mold after giving the lower end of the blanks the shape shown in Fig. 9. Such movement of the 30 plate is effected by mechanism such as the fork 24 in Fig. 1, and actuating mechanism such as illustrated in the La France patent identified above.
- Through the use of construction substantially as described herein, the formation of 35 the usual prominent cutoff scar in the bottoms of bottles and the like containers is avoided. Accordingly, the appearance of the bottoms of the ware is improved and the 40 containers are better able to withstand high internal pressures.
- Modifications may be resorted to within the spirit and scope of the appended claims.
- What we claim is:
- 45 1. The combination of a mold having a cavity opening through one end thereof, a closure plate having a recess in one face thereof, a knife secured to said plate, means for introducing glass into the mold through said opening, means for swinging the knife and plate across the end of the mold and thereby severing the glass and bringing said recess into register with the mold opening, and means for exhausting the air from said 50 recess substantially simultaneously with its movement into register with the mold opening and thereby drawing glass from the mold cavity to fill said recess.
- 55 2. The combination of a mold having a cavity opening through one end thereof, a closure plate having a recess in one face thereof, a knife secured to said plate, means for introducing glass into the mold through said opening, means for swinging the knife and plate across the end of the mold and
- thereby severing the glass and bringing said recess into register with the mold opening, and means for exhausting the air from said recess substantially simultaneously with its movement into register with the mold opening and thereby drawing glass from the mold cavity to fill said recess.
- 60 3. The combination of a suction gathering mold open at one end, means for introducing molten glass by suction into the mold through said end, means for severing the glass at said end, a closure plate having a cup cavity therein, means for moving said plate into a mold closing position in which said cavity is in register with the mold opening and the meeting edges of the mold opening and cup cavity coincide and are substantially coextensive, 65 and means for exhausting the air from the cup cavity substantially simultaneously with its movement into said position of registry with the mold and thereby causing movement of glass from the mold into the cup cavity.
- 70 4. The combination of a mold open at one end to receive a charge of glass, a closure plate having an opening therethrough and a recess therein at one side of said opening, means for moving said plate into position to cause said opening to register with the mold cavity, suction means for drawing molten glass through said opening and filling the mold cavity, means for then moving said closure plate laterally to sever the glass and bring said recess into register with the mold cavity, and means for exhausting the air from said recess substantially simultaneously with its movement into register with the mold cavity.
- 75 5. The combination of a suction gathering mold opening downwardly, a rock shaft, a rock arm carried thereby, a mold closing plate carried by said arm, means providing a cutting edge carried on said plate, said plate having a recess in its upper face, means for introducing a charge of glass by suction into the mold through the lower open end thereof, means for rocking said shaft and thereby moving the cutting edge across the mold for severing the glass and bringing said recess into register with said open end of the mold, said rock shaft, arm and plate being formed with a channel extending therethrough and communicating with said recess, and automatic means actuated by said movement of the rock shaft to open said channel to a source of vacuum and thereby exhaust the air from said recess concomitantly with the movement of said recess into register with the mold.

cavity for causing glass from the mold to fill said recess.

6. The combination of a mold having a cavity opening through one end thereof, a closure plate having a recess in one face thereof, a knife attached to said plate, means for introducing a charge of glass into the mold through said opening, means for swinging the knife and plate across said end of the mold and thereby severing the glass and bringing said recess into register with the mold opening, a vacuum line extending to said recess, and automatic means for connecting said line to a source of vacuum substantially simultaneously with the movement of said recess into register with the said mold opening and thereby exhausting the air from said recess and causing glass from the mold cavity to enter and fill said recess.

7. The combination of a mold having a cavity opening through one end thereof, a closure plate having a recess in one face thereof, a knife attached to said plate, means for introducing a charge of glass into the mold through said opening, means for swinging the knife and plate across said end of the mold and thereby severing the glass and bringing said recess into register with the mold opening, a vacuum line extending to said recess, and automatic means for connecting said line to a source of vacuum substantially simultaneously with the movement of said recess into register with the said mold opening and thereby exhausting the air from said recess and causing glass from the mold cavity to enter and fill said recess, the edges of said recess and mold opening being substantially coextensive and coinciding when the closure plate is in said position of registry with the mold, the walls of said recess being curved to form a rounded end on the parison which is formed in the mold cavity and said recess, without an angle at the meeting edges of the mold cavity walls and the walls of said recess.

8. The combination of a suction gathering mold open at one end, means for introducing molten glass by suction into the mold through said end, means for severing the glass at said end, a closure plate having a cup cavity therein, means for moving said plate into a mold closing position in which said cavity is in register with the mold opening and the meeting edges of the mold opening and cup cavity coincide and are substantially coextensive, a vacuum line extending to said cavity, and automatic means for connecting said line to a source of vacuum substantially simultaneously with said movement of the cup cavity into said position of registry with the mold and thereby causing movement of glass from the mold into the cup cavity.

9. The combination of a mold open at one end to receive a charge of glass, a closure plate

having an opening therethrough and a recess therein at one side of said opening, means for moving said plate into position to cause said opening to register with the mold cavity, suction means for drawing molten glass through said opening and filling the mold cavity, means for then moving said closure plate laterally to sever the glass and bring said recess into register with the mold cavity, means providing a vacuum line extending to said recess, and automatic means for connecting said line to a source of vacuum substantially simultaneously with the bringing of said recess into register with the mold cavity and thereby exhausting the air from said recess and causing a portion of the charge of glass to enter and fill said recess.

10. The combination of a suction gathering mold open at one end, means for introducing molten glass by suction into the mold through said end, a closure plate, a knife, means for moving the knife across said open end of the mold and severing the glass and for bringing said plate opposite the mold opening, and pneumatic means brought into activity by said movement of the plate to cause a pressure of said plate against said end of the mold.

11. The combination of a suction gathering mold open at one end, means for introducing molten glass by suction into the mold through said end, a closure plate, a knife, means for moving the knife across said open end of the mold and severing the glass and for bringing said plate opposite the mold opening, said plate being provided with a recess therein brought into register with said open end of the mold by said movement of the plate, and pneumatic means brought into activity by said movement of said plate and substantially simultaneously with the registration of said recess with the open end of the mold for causing pressure of said plate against the mold and simultaneously causing a movement of glass from the mold into said recess.

12. The combination of a suction gathering mold open at one end, means for introducing molten glass by suction into the mold through said end, means for severing the glass at said end, a closure plate having a cup cavity therein, means for moving said plate into position to close said end of the mold with said cup cavity in register with the mold opening, and automatic means controlled by the movement of said plate into said position to cause a portion of the glass in the mold to enter and fill said recess.

Signed at Toledo, in the county of Lucas and State of Ohio, this 26th day of July, 1929.

OLIVER C. K. HUTCHINSON.
